UNITED STATES PATENT OFFICE.

GEORGE E. HULSE, OF NEW HAVEN, CONNECTICUT, ASSIGNOR TO THE SAFETY CAR HEATING & LIGHTING COMPANY, A CORPORATION OF NEW JERSEY.

REGULATING APPARATUS.

Application filed January 20, 1925, Serial No. 3,546. Renewed July 20, 1927.

This invention relates to regulating apparatus and more particularly to regulating apparatus for electrical systems of distribution.

5 One of the objects of the invention is to provide apparatus of the above nature which is highly efficient and dependable in operation. Another object is to provide such apparatus capable of operating with a high degree of accuracy and whose accuracy is unaffected by varying conditions of use. Another object is to provide apparatus of the 10 above nature wherein certain adjustments are taken care of in the most convenient and practical manner. Another object is to provide apparatus of the above nature adapted to operate dependably without attention for long periods of time. Another object of this 15 invention is to provide an apparatus of the above-mentioned nature capable of maintaining a predetermined standard of regulation even though various mechanical factors may vary in a way that would tend to undesirably affect the intended standard of regulation of the apparatus. Another object is to 20 provide a regulating apparatus in which variability of the action of a spring, due to mechanical fatigue and the like, may be prevented, in a thoroughly practical and dependable 25 manner, from affecting the operation of the regulator. Other objects will be in part obvious or in part pointed out hereinafter.

The invention accordingly consists in the features of construction, combinations of elements, and arrangements of parts as will be 30 exemplified in the structure to be hereinafter described and the scope of the application of which will be indicated in the following claims.

40 In the accompanying drawing in which is shown one of the various possible embodiments of this invention,

Figure 1 is a diagrammatic plan of the apparatus and electric circuits, and

45 Figure 2 is a sectional view of certain parts of the apparatus, the section being taken along the line 2-2 of Fig. 1.

Similar reference characters refer to similar parts in both views of the drawing.

50 Referring now to Figure 1 of the drawing in detail, there is shown a generator 10 which may be driven, for example, at a varying rate of speed from the axle of a railroad car. This generator is provided with a shunt field

winding 11 in which is serially disposed a 55 resistance element 12, the resistance element in this instance taking the form of a carbon pile, the resistance of which varies inversely with the pressure thereon. The external circuit of the generator leads through a main 60 13 to a storage battery 14 and lamps or other translating devices 15, the circuit of the lamps being controlled as by a hand switch 16. The external circuit of the generator is completed to the remaining pole thereof through the 65 main 17 having therein an automatic switch 17^a of a well-known type and a series or current regulating coil 18.

A voltage regulating coil 19 is connected across the generator 10 by leads 20 and 21 as 70 shown, and acts through a core 22 upon a lever 23 pivoted at 24. The magnetic field of the coil 19 pulls upwardly upon the core 22 tending to swing the lever 23 in a clockwise direction about its pivot 24. The series 75 coil 18 acts through a core 25 upon a lever 26 pivoted at 27. The magnetic field of the coil 18 pulls upwardly upon the core 25 tending to swing the lever 26 in a clockwise direction about its pivot 27. The levers 23 and 26 80 are respectively provided with lugs 28 and 29 which, upon the lever 26 being swung upwardly, interlock and cause the two levers to swing while thus interlocked substantially as a single member. The lever 23 is provided 85 with an arm 23^a which engages the movable end of a carbon pile 12. A counter-clockwise rotation of the lever 23, through the arm 23^a, compresses the carbon pile 12, decreasing its resistance, and a clockwise rotation of the 90 lever 23 releases the compression of the carbon pile and increases its resistance. Acting upon the lever 23 in opposition to the pull of the magnetic field of the voltage coil 19 is a tension spring 30 and acting upon the lever 26 95 in opposition to the pull of the magnetic field of the series coil 18, is a tension spring 31. Suitable dash pots 32 and 33 serve to steady the movements of the two levers and prevent "hunting" of the regulator. 100

Considering now the action of the apparatus thus far described, assume first that the generator 10 is stationary; under such conditions the switch 17^a is, of course, open to prevent back discharge of the battery. The voltage coil 19 and the series coil 18 are ineffective and the spring 30 is unopposed, swinging the lever 23 in a counter-clockwise direction to

exert a maximum of pressure upon the carbon pile 12; the spring 31 is also unopposed and swings the lever 27 in a counter-clockwise direction until the core 25 comes against its stop. If now the generator 10 is started its voltage starts to build up rapidly, due to the high compression of and consequent low resistance of the carbon pile 12 in its field. The regulation at the start therefore is such as to permit the generator to build up voltage rapidly as the speed increases, so that it may attain a charging output as soon as practicable, and thus increase the total output.

As soon as the generator voltage builds up to the proper magnitude, the switch 17^a closes and charging of the battery 14 commences, current flowing through the series regulating coil 18. The generator, as its speed increases, rapidly builds up towards its condition of maximum proper output. From this point and beyond the regulation is such as to apply the proper corrective effect upon any tendency of excess of a function of the output of the generator. It may be here noted that the term "function" is used to denote a characteristic of the current, such as its voltage or size. When the battery approaches full charge, the magnets or coils are so chosen as to permit the lever 26 to swing out of interlocking relation with the lever 23, and thereafter the magnet 19 ceases its regulating action through this mechanical connection. The precise time at which the levers disengage, and the relative strengths of the magnets are so chosen as to give the most desirable form of charging curves to meet the various conditions of use. It may here be noted that the term "magnet" is used in a broad sense to cover constructions either of the fixed or movable core types.

The springs 30 and 31 constantly act upon the respective levers 23 and 26 against the action of the coils 19 and 18, and it is highly desirable that the pull of these springs be always maintained substantially constant and uniform in order that dependably accurate regulation be assured. Certain disadvantages are attendant upon the use of springs in that the tension thereof and consequently the force exerted thereby is apt to vary in use, the spring being affected by constant pull, by changing temperatures and by other elements incident to service. These disadvantages of the spring are overcome by the substitution therefor of gravity actuated means, such as a suspended weight. The use of a weight, however, has other distinct disadvantages which are not met with when springs are employed. When springs are employed the moving parts may be mechanically balanced and the operation of the regulator is not affected by the jars incident to service. Moreover, when springs are employed the dash pots 32 and 33 may be of lighter construction than when weights are employed and when consequently

the moving parts are not balanced. A balanced regulator is protected against hunting by the use of small air dash pots which require no attention and are uniform in action under all conditions. Another point is that the characteristic of the change in pull with a change in the position of the core in a coil is more easily balanced by the pull of a spring than it is by a constant force of gravity. In addition, when springs are employed and the parts are balanced, the design may be such that there is practically no load on the pivots of the levers 23 and 26 when the regulator is operating.

Referring now again to the drawing, the levers 23 and 26 are substantially balanced upon the pivot 24 and 27 by means of counter balances 23^b and 26^b properly positioned thereon. Considering first the lever 23, the tension spring 30 is at its lower end connected thereto at 34. Connected to the upper end of the spring at 35 is a flexible cable 36 which passes over a wheel or pulley 37 and has suspended therefrom a weight 38. When the weight 38 is free it pulls upwardly upon the spring 30, thus determining the tension of the spring and hence the force exerted thereby upon the lever 23. When the weight 38 is locked or anchored in position, the upper end of the spring is fixed and the tension of the spring remains at this value determined by the weight 38.

The weight 38 when it moves slides along the face of the part 39 of a fixed T-shaped core 40. This core 40 is provided with a voltage coil 41 connected across the terminals of the generator as shown. This magnet operates as a lock for the weight 38, it being so designed that when the coil 41 is excited the weight is drawn against the surface of the part 39 and prevented from moving in either direction.

When the generator 10 is stationary, there is no voltage across its terminals and no current flows through the coil 41. The weight 38 is thus freely suspended and is free to stretch the spring 30 to the proper tension determined by the magnitude of the weight. Under these conditions, of course, the coil 19 is carrying no current and the core 22 is in its position of maximum downward movement. As soon as the generator 10 is started and the generator begins to build up voltage, the coil 41 is excited and the weight 38 is locked in the position which it has assumed. This position is the proper one to give the correct tension to the spring 30. Thus, the spring 30 is calibrated or adjusted each time the generator 10 stops or each time the lock operated by the coil 41 is released by low voltage of the generator. In this manner, any change in the spring is compensated for by its automatically being adjusted and stretched to the tension which it is desired be uniformly maintained. This construction thus combines the

advantages attained by the use of a spring, as have been pointed out above, and the reliability and uniformity of pull attainable by the use of a weight.

5 Preferably, the weight 38 is provided with a downward extension 42 provided with a slot 43 through which projects a threaded bolt 44. This bolt may be anchored in a suitable fixed support 45, and is provided 10 with a thumb nut 46. The thumb nut 46 may be left loose, permitting free movement of the weight 38 to automatically adjust itself upon stopping of the generator, as above described; in such capacity the bolt 15 44 engaging the slot 43 serves as a guide for the up or down movement of the weight. On the other hand, if desired the coil 41 may be cut out by means of a hand switch 47, and the automatic lock by the magnet not be employed. Then the thumb screw 46 may be tightened up against the part 42, and the weight 38 locked thereby in the position which it assumes when the generator 10 is stationary. As often as desired, upon stopping 20 of the generator, the thumb screw may be loosened and the weight 38 permitted to adjust itself to adjust the tension of the spring.

The spring 31 connected at its lower end at 48 with the lever 26 has connected at its 30 upper end 49 a mechanism substantially identical with that just described in connection with the spring 30, and its action will be understood from the above. A flexible cable 50 passes over a wheel or pulley 51 and has 35 suspended therefrom a weight 52. A magnet coil 53 and core 54 are provided similar to the coil 41 and core 40, and operating in a similar manner. The weight 52 is provided with a downward extension 55 having a slot- 40 ted connection 56 with a bolt 57 which is anchored in a part 58 and provided with a thumb screw 59. The weights 38 and 52 are preferably provided respectively with a plurality of removable and replaceable parts 38^a and 52^a in order that the pull of the weights 45 may be varied and the tension of the springs 30 and 31 correspondingly adjusted.

From the above it will be seen that there is herein provided an apparatus which embodies the features of this invention and achieves the objects thereof including many advantages of the greatest practical importance.

As many possible embodiments may be 55 made of the above invention and as many changes might be made in the embodiment above set forth, it is to be understood that all matter hereinbefore set forth is to be interpreted as illustrative and not in a limiting 60 sense.

I claim as my invention:

1. In regulating apparatus, in combination, a source of current, a variable resistance element adapted to control a function of the output from said source, electro-magnetic 65

means, means responsive to the pull of said electro-magnetic means adapted to vary the resistance of said element, a spring acting upon said last means in opposition to said electro-magnetic means, and gravity actuated 70 means determining the force exerted by said spring.

2. In regulating apparatus, in combination, a source of current, a variable resistance element adapted to control a function of the output from said source, electro-magnetic means, means responsive to the pull of said electro-magnetic means adapted to vary the resistance of said element, a spring acting upon said last means in opposition to said electro-magnetic means, and automatic 75 means adapted to adjust the tension of said spring to a constant predetermined value 80 each time the output of said source is reduced to zero. 85

3. In regulating apparatus, in combination, a source of current, a variable resistance element adapted to control a function of the output from said source, electro-magnetic means, means responsive to the pull of said electro-magnetic means adapted to vary the resistance of said element, a spring acting upon said last means in opposition to said electro-magnetic means, and gravity actuated 90 means adapted to adjust the tension of said spring. 95

4. In regulating apparatus, in combination, a variably driven generator, a variable resistance element adapted to control a function of the output of said generator, electro-magnetic means, means responsive to the pull of said electro-magnetic means adapted to vary the resistance of said element, means acting upon said last means in opposition to the pull of said electro-magnetic means, and 100 means adapted to adjust said last means at 105 each stopping of said generator.

5. In regulating apparatus, in combination, a source of current, a variable resistance element adapted to control a function of the output from said source, electro-magnetic means, means responsive to the pull of said electro-magnetic means adapted to vary the resistance of said element, a spring acting upon said last means in opposition to said electro-magnetic means, a suspended weight 110 for determining the tension of said spring, and means for locking said weight in the position assumed thereby when said electro-magnetic means is ineffective. 120

6. In regulating apparatus, in combination, a source of current, a variable resistance element adapted to control a function of the output from said source, electro-magnetic means, means responsive to the pull of said electro-magnetic means adapted to vary the resistance of said element, a spring acting upon said last means in opposition to the pull of said electro-magnetic means, a suspended 125 weight for determining the tension of said 130

- spring, and means adapted when said generator is running to lock said weight in the position assumed thereby when said electro-magnetic means is ineffective.
5. 7. In regulating apparatus, in combination, a shunt wound generator, a translation circuit therefor, a variable resistance connected with the field of said generator, an electro-magnet having a field proportional to a function of the output of said generator, a member movable in response to variations in the field of said magnet, a connection between said member and said variable resistance adapted upon the field of said magnet increasing in strength to increase the effect of said variable resistance, a spring acting upon said member in opposition to the effect thereon of said magnet, and gravity actuated means connected with said spring for determining the magnitude of the force exerted thereby.
8. In regulating apparatus, in combination a shunt wound generator, a translation circuit therefor, a variable resistance connected with the field of said generator, an electro-magnet having a field proportional to a function of the output of said generator, a member movable in response to variations in the field of said magnet, a connection between said member and said variable resistance adapted upon the field of said magnet increasing in strength to increase the effect of said variable resistance, a spring acting upon said member in opposition to the effect thereon of said magnet, gravity actuated means connected with said spring for determining the magnitude of the force exerted thereby, and means for locking said gravity actuated means in the position assumed thereby when the field of said magnet is ineffective upon said member.
9. In regulating apparatus, in combination, a shunt wound generator, a translation circuit therefor, a variable resistance connected with the field of said generator, an electro-magnet having a field proportional to a function of the output of said generator, a member movable in response to variations in the field of said magnet, a connection between said member and said variable resistance adapted upon the field of said magnet increasing in strength to increase the effect of said variable resistance, a spring acting upon said member in opposition to the effect thereon of said magnet, gravity actuated means connected with said spring for determining the magnitude of the force exerted thereby, and an electro-magnet adapted when said generator is operative to lock said gravity actuated means in the position assumed thereby when said generator is inoperative.
10. In regulating apparatus, in combination, a generator, and regulating means adapted to control a function of the output of said generator, said means including a substantially balanced lever, a spring acting upon said lever, and gravity actuated means for regulating the tension of said spring.
11. In regulating apparatus, in combination, a generator, and a regulator adapted to control a function of the output of said generator, said regulator including a substantially balanced lever, a tension spring connected at one end to said lever, a weight suspended from the other end of said spring, and means for locking said weight in the position assumed thereby when said regulator is inoperative.
12. In regulating apparatus, in combination, a generator, and a regulator adapted to control a function of the output of said generator, said regulator including a substantially balanced lever, an electro-magnet acting thereon, means acting upon said lever in opposition to said magnet, and gravity actuated means for determining the magnitude of the force exerted by said last means.
13. In regulating apparatus, in combination, a generator, and a regulator adapted to control a function of the output of said generator, said regulator including a substantially balanced lever, an electro-magnet acting thereon, a tension spring connected at one end to said lever and acting thereon in opposition to said magnet, a weight suspended from the other end of said spring, and means for locking said last end of said spring in the position to which it is moved by said weight when said regulator is inoperative.
14. In regulating apparatus, in combination, a generator, and a regulator adapted to control a function of the output of said generator, said regulator including a substantially balanced lever, an electro-magnet acting thereon, a tension spring connected at one end to said lever and acting thereon in opposition to said magnet, a weight suspended from the other end of said spring, and means adapted when said regulator is operative to lock said last end of said spring in the position to which it is moved by said weight when said regulator is inoperative.
15. In regulating apparatus, in combination, a shunt wound generator, a carbon pile serially connected with the field of said generator, an electro-magnet having a field proportional to a function of the output of said generator, a lever movable in response to variations in the field of said magnet, a connection between said lever and said carbon pile adapted upon said magnet increasing in strength to increase the resistance of said carbon pile, a spring acting upon said lever in opposition to said magnet, and a weight adapted to act upon said lever through said spring to determine the force exerted by the latter.
16. In regulating apparatus, in combination, a shunt wound generator, a carbon pile serially connected with the field of said gen-

- erator, an electro-magnet having a field proportional to a function of the output of said generator, a lever movable in response to variations in the field of said magnet, a connection between said lever and said carbon pile adapted upon said magnet increasing in strength to increase the resistance of said carbon pile, a tension spring connected at one end to said lever and acting thereon in opposition to said magnet, a weight suspended from the other end of said spring, and means adapted when said regulator is operative to lock said last end of said spring in the position to which it is moved by said weight when said regulator is inoperative. 10
17. In regulating apparatus, in combination, a generator driven at a variable speed from a car axle, and regulating means adapted to control a function of the output of said generator, said regulating means including a magnet, a member adapted to be moved thereby, retracting means acting upon said member, and automatic means adapted to adjust said retracting means to maintain the force exerted thereby substantially constant. 20
18. In regulating apparatus, in combination, a generator driven from a car axle, and regulating means adapted to control a function of the output of said generator, said means including a magnet, a member adapted to be moved thereby, retracting means acting upon said member, and means adapted at each stopping of said generator to adjust said retracting means to maintain the force exerted thereby substantially constant. 30
19. In regulating apparatus, in combination, a variable speed generator, a circuit adapted to be supplied thereby, an automatic switch adapted to connect said circuit to the generator upon the latter attaining a predetermined voltage and to disconnect said circuit from the generator upon the voltage of the latter falling to a predetermined value, regulating means for controlling a function of the output of said generator, said regulating means including electromagnetic means and retracting means against which said electromagnetic means acts, means adapted when effective to adjust said retracting means to maintain the force exerted thereby substantially constant, and means for permitting said last-mentioned means to become effective only at times subsequent to the opening of said main switch. 40
20. In regulating apparatus, in combination, a variable speed generator, a circuit adapted to be supplied thereby, an automatic switch adapted to connect said circuit to the generator upon the latter attaining a predetermined voltage and to disconnect said circuit from the generator upon the voltage of the latter falling to a predetermined value, regulating means for controlling a function of the output of said generator, said regulating means including electromagnetic means and retracting means against which said electromagnetic means acts, means adapted to be supplied thereby, a switch for connecting the generator to said circuit, regulating means for controlling a function of the energy supplied by said generator to said circuit, said regulating means including a coil and retracting means against which said coil acts, and means controlled from the generator side of said switch for adjusting said retracting means to maintain the force exerted thereby substantially constant. 50
21. In regulating apparatus, in combination, a generator, a circuit adapted to be supplied thereby, a switch for connecting the generator to said circuit, regulating means for controlling a function of the energy supplied by said generator to said circuit, said regulating means including a coil and retracting means against which said coil acts, and means controlled from the generator side of said switch for adjusting said retracting means to maintain the force exerted thereby substantially constant. 60
22. In regulating apparatus, in combination, a generator; regulating means for controlling a function of the output of said generator, said means including electromagnetic means and a spring against which said electromagnetic means acts; means adapted to adjust said spring to maintain the force exerted thereby substantially constant; and means under the control of said generator for controlling said adjusting means. 70
23. In regulating apparatus, in combination, a source of current, regulating means for controlling a function of the energy flowing from said source, said regulating means including a coil and retracting means against which said coil acts, and means operative, when said regulating means is ineffective, to adjust said retracting means to maintain the force exerted thereby substantially constant. 80
24. In regulating apparatus, in combination, a generator; regulating means for controlling a function of the output of said generator, said means including electromagnetic means and a spring against which said electromagnetic means acts; and means adapted to adjust said spring to maintain the force exerted thereby substantially constant but operative only when the voltage of the generator is below a predetermined value. 90
25. In regulating apparatus, in combination, a generator; regulating means for controlling a function of the output of said generator, said means including electromagnetic means and a spring against which said electromagnetic means acts; and means operative only when the output of the generator is below a predetermined value to adjust said spring to maintain the force exerted thereby substantially constant. 100

In testimony whereof, I have signed my name to this specification this fifteenth day of January, 1925.

GEORGE E. HULSE.
